UNITED STATES PATENT OFFICE.

ALONZO M. CHENEY, OF CHARLOTTE, MICHIGAN.

IMPROVED CURTAIN-FIXTURE.

Specification forming part of Letters Patent No. 89,126, dated April 20, 1869; antedated October 29, 1868.

Be it known that I, ALONZO M. CHENEY, of Charlotte, Eaton county, Michigan, have invented certain new and useful Improvements in Window-Curtain Fixtures; and I do hereby declare the following to be a full and accurate description of the same, reference being had to the annexed drawing making a part hereof.

My invention relates to that class of curtain-fixtures in which the curtain is kept at the height desired by a weighted tassel, counterpoising the roller on which the shade is taken up; and my improvement consists in the arrangement of the cord connecting the roller and tassel, and operating them.

The drawing represents the fixture applied.

F is the window-frame. The shade S, of any suitable material, is secured, at its upper end, to a strip of wood, which is held firmly to the window-frame by the eyebolts e b e, through which the cords c d pass from the weighted tassel T to the roller R R. This roller, to which the lower end of the shade S is secured in the usual manner, projects sufficiently beyond the shade to allow the flanges or disks, made of any suitable material, f f g g, in diameter somewhat larger than the rest of the roller, to rest on the window-jambs. The distance between these flanges at either end is determined by the amount of cord necessary to be rolled thereon. The cords c d, of the requisite length, are attached to the ends of the roller, respectively, and then led up through the eyebolts e e, thence to the eyebolt c, and so

down to the weighted tassel T, to which they are secured in the usual way. If preferred, one cord may be used, in which case the center is attached to the tassel, and the two ends led up through b, and down through e e to the respective ends of the roller, and there secured.

The method of operating this curtain-fixture is readily seen. When the tassel is pulled down the cords are unwound from the roller, which travels up the window-jambs on its flanges, taking up the shade as it goes. When the tassel is lifted, the weight of the roller carries down the shade, and the cords are wound up between the flanges.

I do not claim the arrangement of the cords c d in connection with the eyebolts e b e and the weighted tassel T; but

What I do claim, and desire to secure by Letters Patent, is—

The application of a flanged roller, substantially in the manner shown, to curtain-fixtures in which the shade is elevated or lowered by means of a weighted tassel and cords, arranged as above described.

In testimony whereof I have signed my name to this specification before two subscribing witnesses.

ALONZO M. CHENEY.
